UNITED STATES PATENT OFFICE.

JAMES BRIGGS, OF IDLE, NEAR BRADFORD, ENGLAND.

SCAVENGERING-MACHINE.

SPECIFICATION forming part of Letters Patent No. 719,733, dated February 3, 1903.

Application filed February 6, 1902. Serial No. 92,915. (No model.)

To all whom it may concern:

Be it known that I, JAMES BRIGGS, a subject of the King of England, residing at Cavendish House, Idle, near Bradford, England, have invented certain new and useful Improvements in Scavengering - Machines, of which the following is a specification.

This invention relates to improvements in scavengering-machines; and its object is to provide a street-sweeping machine that will efficiently gather up and take away the sweepings. For this purpose I employ the usual rotary brush at the rear end of the vehicle; but the brush in this case is parallel to the axis of the vehicle. Immediately in front of the brush is an inclined plate, the rear edge of which touches or almost touches the ground, and a series of troughs, buckets, or carriers mounted upon endless chains pass up from beneath the front of the inclined plate and collect the material thrown over the plate by the brush. The endless chains move in the direction required to carry the buckets upward and then pass over pulleys or guide-wheels at the top, where the buckets are inverted to discharge their contents into a large receptacle beneath. The buckets and chains are preferably inclosed within a suitable casing to prevent the material being blown about, and the buckets or carriers are of such a form that there is no space between them while they are getting filled whereby the material can escape.

To fully describe my invention, reference is made to the accompanying sheets of drawings, forming a part of this specification, in which similar reference - numerals indicate corresponding parts in each of the views.

Figure 1 is a side elevation of my improved machine with certain parts not material to the explanation of the invention omitted. Fig. 2 is a plan view of the same with the middle of the brush broken away. Fig. 3 is a back view of the same. Fig. 4 is an end view, on a larger scale, of one of the buckets attached to the link of one of the endless chains; and Fig. 5 is an elevation of the same, a portion of the bucket being broken away.

50 The body 2 of the vehicle is mounted on

four wheels, only shown in outline by the broken lines 3, the front pair of which are mounted on a swiveling under-carriage in a similar way to an ordinary four-wheeled road-vehicle. A sprocket-wheel 5 is fixed on the nave 6 of the "near" back wheel, and an endless pitch-chain 7, working thereon, drives the sprocket-wheel 8 on the stud 9 and rigidly connected to the spur-wheel 12, engaging the pinion 13 on the end of the shaft 14 of the brush 15. The spindle 14 is mounted in bearings in the ends of the arms 16 and 17, rigidly connected to a shaft 18, journaled in bearings mounted on brackets 20, projecting from the back of the vehicle. An arm 24 is fixed to one end of the shaft 18 and is adjusted by the screw 25 and connecting-rod 26 to regulate the pressure of the brush 15 upon the road. The short chain 28 is introduced between the end of the rod 26 and the arm 24 to allow the brush to lift when passing irregularities in the road. When the vehicle is drawn along in the direction of the arrow, Fig. 1, the brush is rotated in the opposite direction to the wheel 5 and throws all loose material it engages up the inclined plates 30 immediately in front into the traveling buckets 31, carried by the endless chains 33. The buckets 31, moving in the direction of the two arrows, Fig. 1, carry the material up and passing over the guide-wheels 36 and 37 are inverted, and consequently drop their contents into the receptacle 38, which is made with an inclined bottom 39, so that when the side door 40 is loosened the contents of the receptacle will slide out.

The shaft 50, carrying the sprocket-wheels 37, is driven by the chain 61 from the sprocket-wheel 52 on the nave of the "off" back wheel.

The plates 30 are attached to the cross-bar 34, supported by the brackets 20 in such a way that they are free to be lifted to allow them to pass over obstacles in the path.

I claim—

In a device of the class described, the combination with the vehicle-body, of brackets projecting therefrom, a rock-shaft journaled in said brackets, arms on said rock-shaft, a brush journaled in said arms with means for rotating it, an endless carrier coöperating with

said brush, an upright arm on said rock-shaft, a rod slidingly supported beneath the body of the vehicle, a chain connecting said rod with said upright arm, a threaded rod at the 5 front of the hand-wheel engaging a threaded portion on said rod, and a hand-wheel on said threaded rod, substantially as described.

In witness whereof I have hereunto set my hand in presence of two witnesses.

JAMES BRIGGS.
